UNITED STATES PATENT OFFICE.

JAMES HUTCHISON, OF NEWARK, NEW JERSEY, ASSIGNOR TO A. FOLSOM & SON, OF BOSTON, MASSACHUSETTS.

DESIGN FOR OIL-CLOTH.

SPECIFICATION forming part of Design No. 16,865, dated August 24, 1886.

Application filed July 15, 1886. Serial No. 208,162. Term of patent 3½ years.

To all whom it may concern:

Be it known that I, JAMES HUTCHISON, of Newark, in the county of Essex and State of New Jersey, have invented or produced a new and original Design for Oil-Cloth or Carpets; and I do hereby declare the same to be described as follows, and to be represented in the accompanying photograph of it.

It consists of two squares, A B, serrated on their sides and arranged side by side, with a space between them, and in a rectangular space, a b c d, circumscribing and extending between them, as shown. The space about or between the squares is ornamented, as shown, and constitutes a border about them. Each square has in it an ornamental figure, as represented in one of them at C and in the other at D, all being as indicated in the drawing or accompanying photograph.

I claim—

The new and original design for a carpet, as represented and as above described, consisting of the two squares, their figured ground, rectangle, and the ornamental figures in such squares, as shown.
